(57) **CLAIM**

The ornamental design for a shopping bag carrier, as shown and described.

DESCRIPTION

FIG. 1 is a perspective view of a shopping bag carrier showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is an edge view thereof looking from the left with respect to FIG. 1;

FIG. 7 is an edge view thereof looking from the right with respect to FIG. 1; and,

FIG. 8 is a reduced scale, perspective view of a shopping bag carrier showing my new design showing the carrier in its use mode.

The portions shown in broken lines in FIG. 8 are to show environment and form no part of the claimed design.
